(57) **CLAIM**

The ornamental design for a friendship bracelet maker, shown and described.

DESCRIPTION

FIG. 1 is a front perspective view of the friendship bracelet maker showing our new design;

FIG. 2 is a front plan view thereof;

FIG. 3 is a bottom view thereof;

FIG. 4 is a left side view thereof, the right side being a mirror thereof;

FIG. 5 is a top side view thereof; and,

FIG. 6 is a rear view thereof.

The broken lines in the figures are included for the purpose of illustrating portions of the friendship bracelet maker and form no part of the claimed design.
